UNITED STATES PATENT OFFICE.

HIRAM B. SMITH AND GEORGE B. HINMAN, OF ATLANTA, GEORGIA, AS
SIGNORS OF ONE-THIRD TO ED. HOLLAND, OF SAME PLACE.

SELF-CLOSING VISE.

SPECIFICATION forming part of Letters Patent No. 380,461, dated April 3, 1883.

Application filed January 5, 1883. Serial No. 259,894. (No model.)

To all whom it may concern:

Be it known that we, HIRAM B. SMITH and GEORGE B. HINMAN, citizens of the United States, residing at Atlanta, in the county of Fulton and State of Georgia, have invented a new and useful Self-Closing Vise; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The object of this invention is to so improve vises as to make them close automatically and be easily opened without the use of either hand, by reason of which the hands are left free to handle the pieces to be clamped. As vises are usually constructed, one hand being required to close them, the work is usually placed in them with one hand only, which is often difficult and sometimes impossible, in which case the assistance of a second person is requisite, and the same difficulty is also experienced in taking the work out of the vise. These difficulties are entirely overcome by our invention, the details of which will be herein-after fully described, and the parts thought to be new pointed out in the claims.

In the accompanying drawings, Figure 1 is a side elevation, showing all the parts of a cabinet-maker's or carpenter's vise. Fig. 2 is a horizontal section on the line $x-x$, Fig. 1, showing the closing and opening mechanism. Fig. 3 is a vertical section of a portion of the vise-jaws through the center of adjusting-screw. Fig. 4 shows an end view of the lever and the weight.

In the several figures like reference-marks indicate corresponding parts throughout the drawings.

A is the stationary and B is the movable jaw of a vise.

C is an adjusting-screw to regulate the opening between the jaws and forming a pivot for the movable jaw. The screw C is similar to the screw used generally in this class of vises—that is to say, the collar c, against which the washer on the jaw presses, has a hemispherical inner surface, and the washer b' has a corresponding outer surface, for the purpose of

preventing any unequal strain on different parts of the collar by reason of the pivotal movement of the jaw. This screw is also 55 provided with an annular recess, into which the collar fits, for the purpose of keeping the washer on the jaw B in contact with the collar c. The jaw B may, however, be held in position against the collar c by means of a weight 60 or spring; but we prefer the specific construction shown in Figs. 1 and 3. The function of the screw C being simply to adjust and hold the jaw B at the pivotal point, and not to tighten the vise, a small hand-wheel, c', is preferred, as shown, or a crank instead of a lever, as has heretofore been the case in bench-screws.

Near the bottom end of the jaw A is pivoted the lever D, which might be made of a 70 single piece and so shaped as to have its pivotal point at a proper relative height to the weight and the surface that impinges against the jaw B and be passed either through the jaws or at one side of them; but we prefer a 75 double lever, as shown, to pass on both sides of the jaws and to carry a roller, F, between the two parts thereof. Projecting from the jaw A are the pins a, and on the lever D are the brackets d', having indentations d'' on the 80 under sides, that engage with and pivot the lever D on the pins a. On the back end of the lever D is the weight E, which may be adjusted and fastened at the point necessary to exert the required force on the lever, and the front 85 end of the lever projects in front of the vise a sufficient distance to form the pedal H, by means of which the lever D may be depressed.

Between the two parts of the lever D, and journaled thereon, is the roller F, which presses 90 against the inner surface, b, of the jaw B. The height at which the lever is pivoted on the jaw A, the position of the roller F to the pivotal point of the lever, and the lower corner of the rear end of the lever, which corner would come 95 in contact with the floor and stop its downward progress, and the angle of the inner surface, b, of the jaw B, over which surface the roller F travels, should be so proportioned as to prevent a line drawn through the centers of the 100 roller F and pins a from passing farther than to a right angle to the surface b, as that is the point at which the ultimate force is exerted.

The finger b'', fastened to the jaw B and

passing behind the roller F, keeps the lower end of that jaw in contact with the roller, and is provided with a recess in the jaw A, into which it may enter and allow the jaws to come 5 together.

The bar G passes through a mortise in the jaw A, in which it slides, one end being pivoted, as shown, to the jaw B. The preferred position of this bar is near the adjusting-screw, as in that position it has a less distance 10 to move than when near the bottom of the vise, of course excepting such times as are necessary to move the adjusting-screw.

The operation of this device is as follows: 15 The jaws are first set to suit the thickness of the work to be clamped in the vise by turning the adjusting-screw in or out, as necessary, and by lifting the outer end of the lever D until it can be moved to a corresponding position and 20 dropped into one of the indentations d'' in the brackets—that is to say, the indentation that will allow the jaws to close to about a parallel position before the inner end of the lever touches the floor—after which the vise can be 25 opened by depressing the outer end of the lever D by a pressure of the foot, and will close automatically by the gravity of the weight E on the pressure of the foot being removed. In this way work may be more easily and rapidly 30 put into and removed from this vise than a vise in which one hand is requisite to close the vise or open the same.

It will be observed that the weight E may be removed from or toward the pivotal point 35 of the lever D, and that this removal will exert a greater or less force upon the surface b , and that the shortening of the weighted end of the lever by the removal of the fulcrum in adjusting the vise-jaws to take in an article of 40 greater thickness is about compensated for by

the angle of the lever assuming a position before the weighted end of the lever strikes the floor and is stopped thereby that would bring the line of pressure between the pins a and the surface b nearer to a right angle to the 45 surface.

Having thus described our invention, what we claim as new, and desire to secure by Letters Patent of the United States, is—

1. In a self-closing vise, the combination of the 50 jaw A, the adjustable jaw B, and the weighted lever D, adjustably pivoted to the jaw A and impinging against the jaw B, substantially as shown and described.

2. In a self closing vise, the combination of 55 the stationary jaw A, the adjustably-pivoted jaw B, the lever D, pivoted by the brackets d' , having indentations d'' , and the roller F, substantially as shown and described.

3. In a self-closing vise, the combination of 60 the stationary jaw A, the pivoted jaw B, and the weighted lever D, carrying the roller F and the pedal H, substantially as shown and described, and for the purpose specified.

4. In a self-closing vise, the jaws A and B, 65 the screw C, the lever D, carrying brackets d' and pedal H, and having roller d working against the surface b of the jaw B, the pins a , inserted in the jaw A, and the bar G, pivoted to the jaw B and sliding through the jaw A, 70 all combined and operating substantially as described, and for the purpose specified.

In testimony whereof we affix our signatures in presence of two witnesses.

HIRAM B. SMITH.
GEORGE B. HINMAN.
